Fig. 14Fig. 15

FIG. 1 is a front elevational view of a refrigerator cabinet showing my new design;

FIG. 2 is an elevational view of the cabinet taken from the left side thereof;

FIG. 3 is an elevational view of the cabinet taken from the right side thereof;

FIG. 4 is a top plan view of the cabinet shown in FIGS. 1-3;

FIG. 5 is a fragmentary cross sectional view of the door taken on the line 5—5 of FIG. 1;

FIG. 6 is a front elevational view of a modified form of the refrigerator cabinet shown in FIG. 1;

FIG. 7 is an elevational view of the cabinet shown in FIG. 6 taken from the left side thereof;

FIG. 8 is an elevational view of the cabinet shown in FIG. 6 taken from the right side thereof;

FIG. 9 is a top plan view of the cabinet shown in FIG. 6;

FIG. 10 is a fragmentary cross sectional view of the door taken on the line 10—10 of FIG. 6;

FIG. 11 is a front elevational view of another modified form of the refrigerator cabinet shown in FIG. 1;

FIG. 12 is an elevational view taken from the left side of the cabinet shown in FIG. 11;

FIG. 13 is an elevational view taken from the right side of the cabinet shown in FIG. 11;

FIG. 14 is a top plan view of the cabinet shown in FIG. 11; and

FIG. 15 is a fragmentary cross sectional view of the door taken on the line 15—15 of FIG. 11.

The dominant feature of my design resides in the portions shown in full lines.

I claim:

The ornamental design for a refrigerator cabinet, as shown and described.
